UNITED STATES PATENT OFFICE.

RUSSELL DE C. GREENE, OF NICHOLS, FLORIDA.

DRIER.

1,039,385.

Specification of Letters Patent. Patented Sept. 24, 1912.

Application filed September 11, 1911. Serial No. 648,604.

To all whom it may concern:

Be it known that I, RUSSELL DE C. GREENE, a citizen of the United States, residing at Nichols, in the county of Polk, State of Florida, have invented certain new and useful Improvements in Driers; and I do hereby declare the following to be a full, clear, and exact description of the invention, such as will enable others skilled in the art to 10 which it appertains to make and use the same.

My invention relates to new and useful improvements in driers for use in drying phosphate rock, ore, cement or the like, and 15 the object of my invention is to improve the construction and increase the efficiency of driers of the above described character.

A further object of my invention is to provide a drier consisting of an outer cylinder, an inner cylinder revolvably mounted 20 within the outer cylinder, means for passing the hot gases from a furnace through said cylinders and means for passing the rock or ore to be dried through said cylinders.

A further object of my invention is to provide means whereby the rock passes first through the outer cylinder and then back through the inner cylinder while the gases 30 pass first through the inner cylinder and then through the outer cylinder.

With these and other objects in view, my invention will be more fully described, illustrated in the drawings which show a preferred embodiment of my drier, and then 35 specifically pointed out in the claims which are attached to and form a part of this application.

In the accompanying drawings, Figure 1 is a side elevation of my improved drier. Fig. 2 is a central longitudinal section of the same, the inner cylinder being shown in elevation. Fig. 3 is a similar view showing the inner cylinder in section. Fig. 4 is 40 a transverse section on the line 4—4 of Fig. 1. Fig. 5 is a transverse section in the line 5—5 of Fig. 1. Fig. 6 is an end elevation looking toward the furnace. Fig. 7 is a detail plan view of the mechanism for rotating 50 the inner cylinder, the drier being removed to better show the parts.

Referring more specifically to the drawings, in which similar reference numerals designate corresponding parts throughout, 55 my improved drier will be seen to consist primarily of a furnace 1, an inner cylinder

2 and an outer cylinder 3, the inner cylinder being mounted for rotation within the outer cylinder as will be hereinafter fully explained.

The furnace as shown, is of the conventional form having the grate bars 4 and fire-back 5 and the back wall of the furnace is provided with a circular opening 6 into which is extended the flared end 7 of the inner cylinder and as will be readily understood the heated gases from the furnace will pass through the end 7 into this cylinder. This inner cylinder is preferably constructed of boiler plate or other sheet metal suitable of undergoing the intense heat to which it will be subjected and the flared end of this cylinder is preferably formed with a slip joint including an inwardly extending annular flange 7' loosely fitted in the boiler opening and which coacts with an outwardly extending annular flange 7" fixedly secured to the flared end. It will be understood that the flange 7' is not attached to either the outer cylinder or the furnace in any manner but is free to revolve or move backward or forward. Surrounding this inner cylinder adjacent each end are bearing rings 8 each of which bears upon a pair of spaced rollers 9 the trunnions of which are 80 suitably journaled in bearings 10 carried by or formed integrally with a suitable base or platform 11. This base is also provided with bearings 12 in which is journaled a shaft 13 which extends between one of the pairs of rollers and which is provided at one end with a pinion 14 which meshes with a gear 15 which is secured to and surrounds the cylinder 2 adjacent one of its bearing rings. Upon the other end of this shaft is 90 keyed a bevel gear 16 which meshes with a bevel gear 17 carried by a shaft 18 which latter shaft, is adapted to be driven by any suitable engine not shown.

From the above description it will be seen that the cylinder 2 is so mounted that it may be readily revolved and may therefore be adapted to serve as a conveyer of the helical screw type. To adapt it for this purpose the cylinder 2 is internally wound 105 with a plurality of spaced apart strips of Z or angle iron 19, one side of these strips being firmly riveted or otherwise secured to the shell or cylinder while the other side extends inwardly to engage the rock, these 110 strips being so wound as to form a helical screw adapted to convey the rocks from the

outer end of the cylinder to the flared end from which they are discharged through a chute 20 upon a suitable form of conveyer not shown. In order to prevent the rock 5 from remaining in the lower part of the cylinder 2 during its above described progress therethrough I have provided the cylinder with a plurality of spaced apart, longitudinally and inwardly extending ribs or steps 10 21, which as best shown in Fig. 3 of the drawings, are interposed between conveyer threads 19. As will be readily understood the rock is engaged by these steps and is thus carried around the cylinder as well as 15 through the same.

The outer end of the cylinder 2 is closed by a wall 22, preferably formed of sheet metal and secured to this wall and to the cylinder is a centrally positioned, longitudinally extending partition member 23 and a 20 second partition member 24, which members intersect each other at right angles as shown. These members extend inwardly but a slight distance and form a trap to prevent 25 the escape of the rock as it is being fed to the inner cylinder as will be hereinafter described. As shown the angle irons 19 terminate just short of the inner ends of this trap and as a means for feeding the rock 30 to such a point in the cylinder that it will be acted upon by the conveyer the faces of the partition wall are provided with the Z or L-shaped strips 25 which as shown, converge toward each other inwardly, to form 35 chutes through which the rock passes. The outer end of the cylinder is provided adjacent the wall 22 with slots or openings 26 positioned one within each of the sections formed by the partition members and these 40 slots form a means of escape for the gases passing through the cylinder from the furnace and also a means for the inward passage of the rock or ore from the outer cylinder 3, said rock being lifted up and thrown 45 through the slot by means of buckets 27 secured to the outer face of the cylinder 2, one adjacent each of the slots. These slots are preferably formed by forming U-shaped 50 clefs in the cylinder and bending the tongues thus formed inwardly to form inwardly directed flanges which prevent the rock from falling back through the slots as the cylinder revolves. If desired however the slots may be formed by entirely removing 55 portions of the metal and suitable baffle plates may be secured within the cylinder to prevent the escape of the rock.

The outer cylinder 3 as shown, is so proportioned as to form an annular space between it and the inner cylinder and is preferably formed of sheet metal in the same manner as is the inner cylinder, but may be constructed of brick or other preferred material if desired. This outer cylinder is supported at suitable intervals by means of

brackets 28 which are bolted or otherwise secured to the base 16'. The ends of this outer cylinder are provided with inwardly extending annular flanges 29 which co-act with outwardly extending annular flanges 70 30 carried by the inner cylinder to form a slip joint by means of which all escape of rock or gases from between the cylinders is prevented while at the same time the inner cylinder is free to revolve within the outer cylinder. That end of the outer cylinder 3 adjacent the furnace is provided with any suitable form of feed hopper through which the rock or ore may be fed to the drier between the inner and outer cylinders and this 80 end is also provided with an exhaust port or ports 32 from which extends an exhaust pipe 33 the other end of which communicates with the inlet port of an exhaust fan 34 by means of which the gases are drawn 85 out of the drier.

The outer face of the cylinder 2 is provided with a plurality of spirally wound angle irons 35, which are secured to the cylinder by rivets or other preferred means and 90 which as shown, are wound in the opposite direction to that in which the angle irons 19 within the cylinder are wound and are therefore adapted to convey the rock in the opposite direction. 95

The inner cylinder is externally provided with steps of Z or angle iron material 36 arranged parallel to the axis of the cylinder and interposed between the conveyer threads 35 in order to prevent the rock from remaining in the lower part of the annular space 100 between the cylinders. 100

From the foregoing description the operation of the drier will be apparent. The rock or substance to be dried is fed to the outer cylinder by means of the hopper 31, the inner cylinder being rotated meanwhile and is conveyed to the outer end of the outer cylinder where it is picked up by the buckets 27 and passed through the slots 110 31 into the inner cylinder through which it passes and from which it is discharged into the chute 20. The heated gases from the furnace in the meantime pass in through the flared end of the inner cylinder, through the slots 26 to the outer cylinder and back through the outer cylinder from which it is drawn by means of the exhaust fan. It will thus be seen that the ore is fed to that portion of the drier which is coolest and that as it passes through the drier and is thus gradually dried it is continually being brought to a hotter portion of the drier until finally it reaches the flared end of the inner cylinder which is the hottest portion 115 120 of the drier. By this means the drying action is gradual and uniform and this gradual drying together with the fact that the revolving of the inner cylinder keeps the ore continually in motion, prevents it 130

from being baked to the walls of the cylinders and thus clogging the machine.

What I claim is:—

- 5 1. A drier, comprising a furnace, a cylinder rotatably mounted and with one end communicating with said furnace, a second cylinder surrounding the first cylinder, means for supplying the material to be dried to that end of the outer cylinder adjacent the furnace, outwardly extending spirally wound conveyer members secured to the outer face of the inner cylinder and adapted to convey said material through the outer cylinder, means for passing said material from the outer cylinder into the inner cylinder, means for conveying the material through the inner cylinder farthest from the furnace, means for conveying the material through the inner cylinder, means for discharging the material from the furnace end of said inner cylinder, and means for rotating said inner cylinder.
- 10 2. In a drier, the combination with a furnace having an opening in its back wall, of an outer cylinder, an inner cylinder extending through said outer cylinder and revolvable therein, said inner cylinder having one end in communication with the opening in the back of the furnace, means for revolving said inner cylinder, means for supplying the material to be dried to the outer cylinder, and means whereby the revolving of the inner cylinder will cause said material to be conveyed through the outer cylinder in one direction and back through the inner cylinder in the opposite direction.
- 15 3. A drier, comprising an outer cylinder, an inner cylinder extending through said outer cylinder and revolvable therein, means for passing heated gases through said inner cylinder in one direction and back through the outer cylinder in the other direction, and means for passing the material to be dried through the outer cylinder in one direction and back through the inner cylinder in the other direction, the direction of travel of the gases and material at all times being opposite.
- 20 4. A drier, comprising a furnace, a cylinder

rotatably mounted with one end communicating with said furnace, a second cylinder surrounding the first cylinder, means for supplying the material to be dried to that end of the outer cylinder adjacent the furnace, outwardly extending spirally wound conveyer members secured to the outer face of the inner cylinder and adapted to convey said material through the outer cylinder, means for passing said material from the outer cylinder into the inner cylinder, means for conveying the material through the inner cylinder, means for discharging the material from the inner cylinder, and means for rotating the inner cylinder.

5. A drier, comprising a furnace, a cylinder with one end communicating with said furnace, a second cylinder surrounding the first cylinder, means for rotating the first cylinder, an exhaust port in the second cylinder, an exhaust fan, communicating means between said port and fan, a supply hopper adjacent said exhaust port, spirally wound conveyer members secured to the outer face of said first mentioned cylinders, the outer end of said first mentioned cylinder being slotted, buckets carried by said first mentioned cylinder and adapted to discharge through said slots, longitudinally extending partition walls positioned in the slotted end of said cylinder, spirally wound conveyer members carried by the inner face of the first mentioned cylinder, said members being wound in the opposite direction to the first mentioned members, and longitudinally extending spaced apart steps positioned between said members.

In testimony whereof, I affix my signature, in presence of two witnesses.
